UNITED STATES PATENT OFFICE.

ROBERT HENRY CHITTY, OF MOSHEIM, TEXAS.

COTTON-STALK KNOCKER.

SPECIFICATION forming part of Letters Patent No. 651,298, dated June 5, 1900.

Application filed June 1, 1899. Serial No. 718,984. (No model.)

To all whom it may concern:

Be it known that I, ROBERT HENRY CHITTY, a citizen of the United States, residing at Mosheim, in the county of Bosque, State of Texas, have invented certain new and useful Improvements in Cotton-Stalk Knockers; and I do hereby declare the following to be a full, clear, and exact description of the invention, such as will enable others skilled in the art to 10 which it appertains to make and use the same.

My invention relates to cotton-knockers, and more particularly to a device of this class which may be readily attached to or combined with a wheeled cultivator of usual form.

15 With these objects in view my invention consists in one embodiment thereof of sills removably secured to the frame of a cultivator and having journaled at their rear ends, which project beyond the wheels of the cultivator, a shaft bearing a drum having radially-extending arms and which is adapted to be rotated to knock the stalks against the lower bar of a U-shaped frame, whose ends are connected with said sills and whose web 25 lies transversely of the underside of the arms.

In a second embodiment of my invention I journal upon the axle of a wheeled cultivator-frame and in a hanger depending therefrom a vertical shaft having adjacent to its lower 30 end radially and horizontally extending arms adapted to be rotated between the horizontal bars of a frame suspended from the axle of the cultivator-frame and against which bars the arms are adapted to knock the cotton-stalks.

35 In the drawings forming a portion of this specification, and in which like letters of reference indicate similar parts in the several views, Figure 1 is a perspective view of one 40 form of my invention. Fig. 2 is a rear elevation of a second form of my invention, and Fig. 3 is a side view of the knocker-frame. Fig. 4 is a detail of a double yoke, and Fig. 5 is a detail of a shaft bearing upon the axle.

45 Referring now to the drawings, and more particularly to Fig. 1 thereof, in operating in accordance with this form of my invention I provide an ordinary cultivator-frame, consisting of an axle *a*, having wheels *b* thereon, 50 and to which axle are connected thills *c*, having a tongue *d* extending therefrom. Adjacent to the base of the tongue is pivoted

a doubletree having singletrees connected therewith, and in the rear of the doubletree is supported a seat for the driver of the apparatus. From a cultivator-frame of this nature I remove the sills and the teeth carried thereby, and for them I substitute a pair of sills *e* and *f*, the forward ends of which are 55 removably connected with the thills by means of yokes *g* and *h* or in any other desired manner. The sills are also connected with the axle, beneath which they pass, by means of double yokes, as shown in detail in Fig. 4 of the drawings, the web of which double yoke 60 lies upon the axle and the depending legs of which inclose the adjacent sill. Cross-plates impaled upon the legs of the double yoke are 65 held in position by means of nuts engaging the threads of said legs.

70 At the rear ends of the sills *e* and *f* are arranged bearings *i* and *k* for the reception of the shaft of a drum *l* and which shaft has at one end a sprocket-wheel *m* in alinement with a second sprocket *n* upon the hub of the corresponding wheel of the cultivator-frame, and upon these two alining sprockets is arranged 75 a chain *o*, through the medium of which motion is transmitted from one to the other.

Depending from the ends of the sills *e* and *f* are the vertical legs of a U-shaped knocker-frame *p*, said legs being connected by a transverse connecting-web *r*, intermediate of which web and the drum *l* are adapted to rotate a series of radial arms *t*, carried by said 80 drum, the radial extension of said arms being sufficient to allow them to just clear the frame. Thus it will be seen that as the machine moves forwardly the drum and its arms will be rotated in a direction to cause the 85 lower arms to travel rearwardly and, engaging the cotton-stalks, knock them against the web *r* of the knocker-frame.

In Figs. 2 and 3 of the drawings I have 90 shown a cultivator-frame having wheels and from which the sills and teeth have been removed. In this form of my invention I arrange upon the axle *A* of the cultivator-frame 95 and depending therefrom centrally thereof a hanger *B*, having a bearing *C* below the axle and in alinement with a second bearing *D*, carried by the axle. In these bearings is journaled a vertical shaft *E*, having at its upper 100 end a bevel-gear *F*, meshing with a similar

gear G upon a shaft carried in brackets I and K upon the axle A and which shaft H has at its opposite end a bevel-gear L, meshing with a similar gear M upon the inner side of an adjacent wheel of the cultivator-frame and which gear M is concentric with and adapted to turn with the wheel.

Suspended from the hanger B and at right angles to the axle A is a knocker-frame, comprising upper, lower, and intermediate horizontal and parallel bars N, O, and P, respectively, connected at their adjacent ends by vertical cross-pieces R and S, as shown, which bars and cross-pieces inclose two rectangular spaces U and V, vertically of which passes the shaft E, which has a bearing in the lower bar of the knocker-frame, as shown.

Upon the shaft E and intermediate of the upper and lower bars of each space U and V is arranged a collar W, having radially-extending knocker-arms X, adapted to rotate in horizontal planes and knock the cotton-stalks against the bars of the knocker-frame. The operation of this form of my invention is evident from an inspection of the drawings in connection with the foregoing description, and it is not necessary that I go into further detail.

It is evident that I may vary the specific construction and arrangement herein shown and described and that I may build the complete apparatus or that portion attached to the cultivator-frame and that I may employ whatever material may be deemed expedient without departing from the spirit of my invention.

In order that the shaft H may be readily removed from the axle A, the brackets containing the shaft-bars are held upon the axle A by means of bolts A', passed through perforations in said brackets and lying at opposite sides of the axle A, plates B' being impaled upon said bolts and held thereon by means of nuts C', engaging the threads of the bolts. The hanger B is likewise removably

connected with the axle A by means of bolts D', passed through alining perforations in the hanger and axle. The bearing of shaft E upon the axle A is in a recess in the latter, as shown in detail in Fig. 5 of the drawings, 50 a coöoperating plate G', having also a recess therein, being bolted over said shaft and held in place by means of bolts passed there-through and through the axle A.

Having thus described my invention, what I claim is—

1. A cotton-stalk attachment for cultivators comprising a frame adapted for removable attachment to a cultivator, said frame including an upper attaching portion, and a lower portion at right angles thereto and adapted to lie below the axle, a drum journaled in the frame, arms carried by the drum and adapted for rotation therewith to knock stalks against the frame therebelow, and means for rotating the drum.

2. A stalk-knocker attachment for cultivators comprising a frame adapted for removable attachment to a cultivator, said frame including an upper portion having means for attachment to the axle of the cultivator to lie therebelow and in the plane thereof and a lower portion lying at right angles to the upper portion and in the direction of the progress of the cultivator, said lower portion including upper, lower and intermediate horizontal bars, a drum journaled vertically in the frame and having upper and lower arms adapted to move between said bars and co-operate therewith, and a shaft adapted for attachment to the axle and for operative attachment to a wheel of the cultivator and the drum for operating the latter.

In testimony whereof I affix my signature in presence of two witnesses.

ROBERT HENRY CHITTY.
